UNITED STATES PATENT OFFICE.

THOMAS HALL, OF RIDGWAY, PENNSYLVANIA.

GOVERNOR.

Application filed October 10, 1919. Serial No. 329,684.

To all whom it may concern:

Be it known that I, THOMAS HALL, a citizen of the United States of America, and resident of Ridgway, Elk County, Pennsylvania, have invented a Governor, of which the following is a specification.

My invention relates to improvements in governors; and especially to improvements in governors particularly intended for use 10 in connection with steam and other fluid pressure turbines, and comprises an air-pressure-producing device, preferably driven by the machine to be governed, and, in the case of a steam turbine governor, preferably comprising a fan mounted on and driven by the rotor shaft of the turbine; the governor further comprising a piston or pistons upon which the air pressure thus produced acts, together with means actuated 20 by movement of such piston or pistons for effecting control of an admission valve or other controlling means of the turbine or machine to be governed. My invention consists in the novel governing means just hereinbefore stated, together with other features, 25 all as hereinafter described and particularly pointed out in the appended claims.

The objects of my invention are, to provide improved and simplified governing 30 means, particularly for steam turbines and the like, which shall be capable of being adjusted for extreme sensitiveness, the frictional losses in which shall be small, the wear in which shall be small, and which 35 shall not be affected by viscosity of liquid, by leakage, and by other conditions such as particularly affect governing devices heretofore devised and employing a liquid, rather than a gas such as air.

40 I will now proceed to describe my invention with reference to the accompanying drawings, and will then point out the novel features in claims:

Figure 1 shows a side elevation of my improved governing device, and

45 Figure 2 an end elevation thereof, together with associated parts of a steam turbine.

Figure 3 shows a central vertical section 50 of the admission valve of the turbine and control means therefor including the pistons and piston chamber of my improved governing mechanism; and

55 Figure 4 is a fragmentary detail vertical section through the fan chamber and piston chamber of my governor.

Figure 5 is a fragmentary vertical section of a portion of the piston chamber and the adjacent portion of the blower casing, showing the ports leading from the blower casing into the piston chamber.

In the drawings, 1 designates the casing of the turbine to which my governor is fitted, 2 designates the rotor shaft of the turbine, 3 the casing of the blower of my turbine, and 4 (Figure 4) the fan of that governor, mounted upon the rotor shaft 2. 5 designates a piston chamber, divided as indicated in Figure 3, into two cylinders 6—6 by a partition 7; within which cylinders 6—6 are corresponding pistons 8—8 mounted upon a common piston rod 9 which passes freely through suitable bearings in the top and bottom of the piston chamber 5. The employment of two pistons, in separate cylinders, is a mere duplication designed to afford increased power, and obviously the number of pistons, and corresponding cylinders, may either be less or greater.

At its upper end, the piston rod 9 is connected by a horizontal link 10 to another piston 11 located within a cylinder 12; and also is connected to the valve rod 13 of a pilot-valve 14 working in a valve-chamber 15 having ports 16 and 17 connecting it to the cylinder 12 at points above and below the piston 11 respectively. The valve chamber 15 is provided with an inlet port 15^a connected to a suitable source of fluid pressure. The horizontal lever 10, connected 90 not only to the piston rod 9, but also to the piston 11, and to the valve rod 13, and the pilot valve 14, with valve chamber 15 having ports as specified, constitutes a familiar "follow-up" mechanism whereby the pilot 95 valve 14, under control of the piston rod 9, operates the valve-motor comprising the piston 11 and cylinder 12. As is common in such cases the piston 11 is connected by a main valve rod 22, to the admission valve of 100 the turbine, which in this case is shown as a double-balanced valve, comprising valves 23, adapted to seat on valve seats 24. 25 designates the admission duct to this main turbine valve, and 26—26 designate ducts leading from said admission valve to the turbine. I do not deem it necessary to describe further the action of the valve-operating motor 11—12, the follow-up operating mechanism therefor, or the balanced admission 110 valve 23, as these parts are all well known.

As will be obvious, in action the fan 4, by

its rotation, produces an air pressure which is static, except as variations in speed of the driving shaft 2 of the turbine or other driving means for the fan, may vary; and this pressure is communicated through ports 27 (Figure 4) to the cylinders 6, beneath the pistons 8 therein. The consequent tendency of these pistons to rise is balanced, except as such pressure may vary due to varying speed of the driving means 2, by a spring 28 (Figure 2) acting through a spring rod 29, a pivoted horizontal lever 30, and a rod 31 which forms a downward continuation of the piston rod 9, being connected, therefore, to the air pistons 8.

As indicated, the connection of the spring rod 29 to the lever 30 is adjustable, and by adjusting this point of connection lengthwise of the lever 30, the sensitiveness of the 20 governor may be adjusted; by moving that point of connection closer toward the pivotal point of the lever, the governor is made more sensitive, and by moving the point of connection in the opposite direction, the 25 governor is rendered less sensitive, i. e., more stable. There is also provided on the spring rod 29 a nut 29^a engaging the spring 28, by means of which nut the sensitiveness of the 30 governor may also be adjusted; by screwing this nut further up on the spring, the 35 governor is made more stable, and by screwing said nut down the governor is made more sensitive.

Above this spring 28 there is provided a 35 screw 32 secured at its lower end to the top of the spring, also a nut 33 controllable by a hand wheel 34, by which nut and hand-wheel the pull exerted by this spring 28 may be varied, so as to correctly balance the 40 spring action with respect to the pressure exerted by the compressed air against the pistons 8. In some cases I also provide an electric motor 35 driving a worm 36 acting upon a worm wheel 37 connected to this nut 33; the said motor and its connections affording means for adjustment of the governor from a distant point, as for example, from a switch-board. The connection between the worm wheel 37 and the nut 33 is 45 through a simple pin-clutch device 39, whereby, if desired, adjustment of the governor may be effected by the hand-wheel 34 without operation of the motor 35.

The action of this governor will now be 50 obvious: In case the speed of the turbine or other machine driving the fan wheel 4 should increase beyond a predetermined rate, the air pressure against the pistons 8 will increase, and therefore the pistons 8 will ascend slightly, such motion being communicated through the lever 10 to the valve 14, which rises and permits fluid pressure to flow from the inlet port 15^a through the channels or grooves 14^a in the valve, and 55 through the port 16 into the cylinder 12

above the piston 11. The valve 14 also connects the space or chamber below the piston with the exhaust chamber 18, which is provided with the exhaust port 19. The piston therefore descends with consequent lowering of the main admission valves 23; the motion of the piston 11 being followed, of necessity, by readjustment of the position of the pilot valve 14. This is as is common in these follow-up mechanisms. Conversely, 70 if the speed of the machine driving the fan 4 decrease, the air pistons 8 will lower slightly under the influence of the spring 28, with corresponding operation of the valve 14 and piston 11. In this case the fluid 75 pressure from the inlet 15^a passes through the channels 14^a through the recess 21 and port 17 into the chamber or space below the piston 11, while the space above the piston 80 exhausts through port 16 into exhaust chamber 18^a which connects with exhaust chamber 18 and exhaust port 19.

In practice, in one particular design, rotation of the fan 4 at about 3600 revolutions per minute has given an air pressure of 90 about twelve inches of water acting against the pistons 8.

I am aware that heretofore governing devices have been proposed, wherein a liquid pump or the like, driven by a turbine, has 95 been caused to act upon a piston or pistons, with a pressure varying according to the speed of the turbine, the so-varying pressure effecting corresponding adjustment of a control valve of the turbine. To the use of liquid 100 in this manner, as distinguished from a gas such as air, there are several disadvantages. For example, the pump must be supplied constantly with liquid. The action of the pump creates heat which may evaporate the 105 liquid; it also creates pressure which may lead to leakage; and leakage may result from other causes as well, as will be obvious. Any leakage tends to unbalance the governor action. Conceivably, also, the liquid may freeze at 110 a time when the pump is not working; also the viscosity of the liquid may enter into the problem, so that the action of the governing mechanism may differ with changes of temperature. It is extremely important that a 115 governor shall always operate; for if the governor fail to operate, dangerous speeding up may result, with, sometimes, accidents. On the other hand, when air is employed, there is no danger of failure of 120 supply of the working medium of the governor; for it is ever present, always surrounding the blower, and, practically speaking, its qualities such as viscosity, elasticity, etc., never change. Diurnal changes of barometric 125 pressure are not important, and differences in barometric pressure of different locations can be taken care of in design. Frictional losses are much less than when a liquid is employed, and there is no wear due 130

to cutting action as is apt to be the case when liquid is employed; likewise there is no danger of stoppage of ports such as may well occur when liquid is employed.

5 Within the cylinder 12, and above the piston 11, I have shown a spring 40 which, by acting upon the piston, insures closing of the valves 28 in case for any reason the supply of liquid under pressure to the pilot valve 10 should fail.

In connection with the governor as herein described, I have also illustrated a certain "emergency trip," as this device forms no portion of the present invention, I do not 15 describe it herein.

What I claim is:

1. A governing device such as described, comprising an air fan blower driven by a machine to be governed, pressure-actuated 20 means comprising a piston chamber and a piston therein, said chamber being connected to the blower to be continuously subjected to the varying air pressure produced by the varying speed of the blower, means operatively connecting said piston to the controlling valves of said machine, a balancing spring, and means connecting said spring to said piston comprising a pivoted connecting lever, means for varying the leverage exerted 25 by said spring through the lever to the piston to vary the sensitiveness of the governor, and means for adjusting the tension of said spring to balance its reaction with respect to the fluid pressure exerted upon the piston. 30

35 2. A governing device such as described,

comprising an air fan blower adapted to be driven by a machine to be governed, pressure-actuated means comprising a piston chamber and a piston therein, said chamber being directly connected to the blower 40 to be affected instantly by varying air pressure due to varying speed of the blower, means operatively connecting said piston to the controlling valves of said machine, a balancing spring, and means connecting said 45 spring to said piston comprising means for varying the sensitiveness of the spring reaction.

3. A governing device such as described, comprising an air fan blower adapted to be 50 driven by a machine to be governed, pressure-actuated means comprising a piston chamber and a piston therein, such chamber being directly connected to the blower to be instantly affected by varying air pressure 55 due to varying speed of the blower, means operatively connecting said piston to the controlling valves of said machine, a balancing spring, means connecting one end thereof to said piston, and means acting upon the 60 other end of said spring to adjust the pressure exerted thereby.

In testimony whereof I have signed this specification in the presence of two subscribing witnesses.

THOMAS HALL.
